UNITED STATES PATENT OFFICE

104,290

DESIGN FOR A FISHING LURE

Paul D. Paulson, Oak Park, Ill.

Application August 17, 1935, Serial No. 58,170

Term of patent 14 years

To all whom it may concern:

Be it known that I, Paul D. Paulson, a citizen of the United States, residing at Oak Park, in the county of Cook and State of Illinois, have invented a new, original, and ornamental Design for Fishing Lures, of which the following is a specification, reference being had to the accompanying drawing, forming a part thereof;

Figure 1 is an inside view in elevation of a fishing lure, showing my new design;

Figure 2 is a side view in elevation of the lure shown in Figure 1; and

Figure 3 is an outside view in elevation of the lure shown in Figure 1.

The essential features of my design consist in a spoon having a relatively wide elliptical shaped rear end portion of substantially concavo-convex construction, the general outline of which tapers forwardly to the end of the lure and the concavo-convex portion merging intermediate the ends of the lure into a substantially plane portion

extending in offset relation from the general plane of the concavo-convex portion, the design of said lure at and adjacent its rear end being characterized by providing crimping on both sides of the longitudinal axis of said concavo-convex portion giving said portion the appearance of a raised ridge at the central part thereof which is narrow adjacent the rear end of said lure and diverges forwardly to flatten out adjacent the merging of said concavo-convex portion with said plane portion, and the design of said lure at its forward end being further characterized by a solid mass of material on the inside face thereof which is triangular in appearance longitudinally and transversely of said lure.

I claim:

The ornamental design for a fishing lure substantially as shown and described.

PAUL D. PAULSON.
